UNITED STATES PATENT OFFICE.

LUIS MANZANO, OF HUELVA, SPAIN.

CENTRAL BUFFER WITH AUTOMATIC COUPLING FOR RAILWAY-CARS.

1,068,256.

Specification of Letters Patent.

Patented July 22, 1913.

Application filed May 18, 1912. Serial No. 698,305.

To all whom it may concern:

Be it known that I, LUIS MANZANO, a subject of the Spanish King, and resident of Huelva, Spain, have invented certain new and useful Improvements in Central Buffers with Automatic Couplings for Railway-Cars, of which the following is a specification.

This invention relates to an axial or central buffer provided with an automatic coupling for railway cars and more especially for light railway cars and mine cars, the object of the invention being to provide a buffer of the kind described which is very simple and comprises neither springs nor other sensitive parts which can only resist with difficulty the stresses resulting from tractive efforts, shocks and the like.

The coupling buffer which forms the subject matter of this invention comprises only three parts *i. e.* the buffer proper which is hollowed out in an axial direction, a shackle or link and a locking latch, these parts being arranged in such a manner that the simple throwing together of the two central buffers produces the pushing back of the lock bolt which again falls automatically back into its engaging position thus locking the coupling.

As readily seen in the device forming the subject matter of this invention no handle or similar member has to be actuated either from the car or from the outside of the track. It follows therefrom a considerable simplifying of construction, economy of time and absence of danger as well as the reduction to the admissible minimum of the cost of upkeep and of the number of workmen.

In the accompanying drawings: Figure 1 is a side elevation view with a section of parts of the coupling; Fig. 2 is the end elevation view of one of the buffers; Fig. 3 is the top plan view corresponding to Fig. 1; Fig. 4 shows a side elevation view with parts shown in section of a somewhat modified form of embodiment.

The coupling link or shackle 1 has the form of a figure 8 or a similar shape.

The locking latch or bolt has a particular shape. Its front part is provided with a rounded inclined surface which is struck by the 8 shaped link 1 when the buffers are thrown together. The body of the locking latch has been provided with a vertical slot 5 through which a bolt 5', provided on the

corresponding buffer, is passed. When the locking bolt occupies its lowermost position, the locking bolt is suspended from this bolt which serves as a fulcrum for it.

The upper part of the lock bolt is shaped so as to form a handle 19 the object of which will be pointed out later on.

For the purpose of guiding or housing the locking latch the buffer has been provided in its upper and lower parts respectively with longitudinal openings 4' and 6' which pass through the corresponding parts of the buffer.

Let us assume now that both buffers are separated from each other and that the buffer which is positioned on the left hand side in the drawing be provided with an 8 shaped link or shackle 1 which is held in position by the locking latch 2. Let us suppose besides that both buffers are thrown into contact with each other. The free end of the link or shackle 1 then strikes the bottom surface of the neighboring buffer and slides upward on this surface until it strikes against the locking latch 2 which is thus pushed back toward the inclined rear surface 4 of the lower opening or seat 4' of the buffer. During this motion the locking latch 2 slides upward along this surface 4, being guided through the medium of its slot 5 by the cross bolt 5'. The locking latch 2 eventually arrives in the position shown in dot and dash lines in Fig. 1, its lower part resting against the rear surface 6 of the upper guide slot 6' of the buffer.

The hollow of the buffer extends sufficiently to the rearward as at 3' (Fig. 1) to allow the front part of the coupling link to slide past the rear surfaces 6 of the upper slot 6' and this in such a manner that the locking latch 2 be allowed to fall under the influence of its own weight into the engaged eye of the figure 8 shaped link thus locking the coupling in position.

The locking latch 2 has been provided at its front part and more especially at the upper end of the inclined striking surface 2' with a shoulder 7 which when the coupling is engaged presses from below against the metal of the buffer at the front end of the upper guide slot 6' and serves to prevent during the running of the train the locking latch 2 from jerking upward or being pushed upward and from thus producing the separation of the cars of the train.

The coupling described above allows the

cars to be very easily separated from each other. It will be sufficient to attain this result to grasp the handle 19 of the latch and to pull it upward. The suppleness of this coupling is very great not only in the direction of its height but also in the direction of its width which results from the simple inspection of the drawings. The narrowed central part of the figure 8 shaped link 5 or shackle 1 ascertains in connection with the enlarged shape of the buffer mouth a very great freedom of motion in the curves while the enlargement of the buffer mouth exists also in the vertical direction and 10 allows the regular coupling of cars the buffers of which are not for one reason or another at the same height or level.

One 8 of the ends of the bolt 5' is hook shaped and serves to carry a spare link or 20 shackle.

The arrangement shown by Fig. 4 is employed in all cases where it is desirable that the coupling link or shackle does not form an independent part. To this end the buffer 25 has been provided at its lower part with two ears 9 through which passes a bolt 10 and between which the eye of an eye bolt 11 is adapted to oscillate on the bolt 10 and this in the longitudinal direction of the buffer. 30 The central part of the figure 8 shaped coupling link or shackle 1 is provided with a vertical hole 12 in which a ball headed bolt 13 is held so as to allow its motions in all directions. The outer end of the parts 11 35 and 13 is screw threaded and carries a nut locked in position by means of a cotter pin these nuts holding two washers 14 and 14' in position which in turn hold a chain link 15 having the usual shape the arrangement 40 being such that this chain link is holding the parts 11 and 13 together while allowing the pivoting motion of the latter. Now, when the figure 8 shaped coupling link or shackle 1 is not in use it hangs freely 45 downward as shown on the right hand side of Fig. 4. When it is desired to couple two cars, one grasps the figure 8 shaped link at the end 16 and rotates it in such a manner that its end 17 can be slid in the mouth 50 of the corresponding buffer. During this operation the locking latch 2 like in the instance described above will hold the link and this in such a manner that it will be ready for insertion into the second buffer. 55 Under each edge of the buffer a depression

18 has been provided which in spite of the presence of the bolt 13 allows the buffers to come together without being hindered. Otherwise the arrangement, function and advantages are the same as in the first form 60 of embodiment.

Having now fully described my said invention, what I claim and desire to secure by Letters Patent, is:

1. A car coupling comprising a coupling 65 head having a centrally disposed depression, the lower wall of which inclines downwardly toward the front of the head, said head having a vertical slot which intersects the depression, the rear wall of the vertical slot 70 adjacent the downwardly inclined wall inclining up from the bottom and toward the rear, a latch operating in the vertical opening and formed with a slot, the lower edge of the latch being beveled, the beveled surface being normally spaced from the rear inclined wall of the vertical slot, to permit of a free movement of the latch before contacting with said rear inclined portion, the lower front edge of the latch being inclined, 80 a pin engaging the slot in the latch to support the latter, and a link formed with a latch engaging opening, the end of the link contacting with the lower inclined front edge of the latch and forcing the lower 85 beveled edge against the inclined rear wall of the vertical slot and thereby elevating said latch for its engagement with the opening in the link.

2. A car coupling comprising a head 90 formed with a link receiving opening and a vertical latch receiving seat the rear wall of the latter being inclined, a latch mounted on the head, means for mounting the latch to permit it to swing in an upward and 95 rearward direction, the front edge of the latch being inclined and its bottom being beveled, the beveled portion being normally spaced from the inclined wall of the vertical seat to permit of a slight free movement of 100 the latch before the latter contacts with the rear wall when a link is thrust against the front inclined portion, whereby to elevate said latch.

In testimony whereof I have hereunto set 105 my hand in presence of two witnesses.

LUIS MANZANO.
